UNITED STATES PATENT OFFICE

ERNEST D. ANDERSON, OF NEW YORK, N. Y., ASSIGNOR TO TROY LAUNDRY MACHINERY COMPANY, INC., OF NEW YORK, N. Y., A CORPORATION OF DELAWARE

GARMENT PRESS

Application filed January 12, 1928. Serial No. 246,228.

This invention relates to pressing machines and relates more particularly to high power machines adapted for garment pressing, laundry ironing and work of similar character.

5 An object of the invention is to provide an improved high power pressing machine designed to close upon the work rapidly under light pressure and then to subject the work to heavy pressure.

10 Another object is the provision of a pressing machine operated by fluid pressure, wherein two cylinders are used, one of the cylinders being small and serving initially to close the pressing members and the other cylinder being large and serving to subject material in the press to a final heavy pressure.

15 A further object of the invention is the provision of a fluid operated press adapted, through the use of two cylinders of different sizes, to operate with a minimum volume of fluid.

20 Another object of the invention is the provision of a safety device which permits a press to be closed only by the use of two hands.

25 An additional object of the invention is the provision of an improved form of valve structure for use with fluid operated presses.

Presses of the type adapted quickly to close upon the work and then to subject the work

30 to heavy pressure are well known in the art. However, these presses have inherent disadvantages, one of the major of which is the requirement of a relatively large amount of power. Presses have been made which utilize fluid under pressure as a power medium.

35 Some of these presses have utilized a single cylinder for producing the result and others have used two cylinders, the function of one of which was initially to close the press and the function of the other to give the material in the press a final heavy squeeze. While many of these machines have proved satisfactory in certain cases they have had the disadvantage that a relatively large volume of fluid under pressure was required for their operation.

40 According to my invention I provide a press utilizing two cylinders, within one of which moves a piston of small diameter and within the other of which moves a piston of

very large diameter. The function of the smaller of these, which utilizes but a small volume of fluid, is initially to close the press and the function of the larger, which moves relatively to its piston but a small distance 55 and which requires but a small volume of fluid, is to give the jaws of the press a final heavy squeeze. In carrying out my invention I provide locking means which hold the small piston in its extended position after the same 60 has been forced to such position by fluid pressure as an incident of the closing of the press, said locking means serving to actuate a valve for admitting fluid under pressure to the larger of said cylinders which then gives 65 the jaws of the press a final heavy squeeze. In order to insure automatic opening of the press at the desired moment I provide a tripping mechanism acting responsive to release of the fluid pressure in the large cylinder, to 70 release the above mentioned locking means and permit the jaws of the press to be opened under the action of a spring. For controlling the admission of fluid to the cylinders of the press I provide a valve mechanism operable 75 by a system of levers, so interconnected that it is necessary for the operator of the press to use both hands in order to open the said valve.

70 The above mentioned and other objects and 80 advantages of the invention and the manner of attaining them will be made clear in the following description of a particular embodiment of my invention, taken in conjunction with the accompanying drawings.

85 Referring to the drawings, Fig. 1 illustrates in elevation a laundry press constructed in accordance with my invention.

Fig. 2 illustrates partly in vertical section the power means of the press shown in Fig. 1. 90

Figs. 3 and 4 are sectional views of the valve shown attached to the press in Fig. 1.

Fig. 5 is a front view of a portion of the press closing mechanism shown in Fig. 2.

Fig. 6 is a front view of the press showing 95 the two hand control for controlling the closing of the jaws of the press.

Fig. 7 is a view of the press shown in Fig. 1 in open position.

In the drawings, reference numeral 1 indi- 100

cates a frame member of a press constructed in accordance with my invention, this frame member comprising table portion 2 and upright arm 3. Mounted on the table 2 is a buck 4 and pivotally attached to the arm 3 is a lever arm 5, to one end of which is secured a presser head 6. Pivotally secured to the other end of lever arm 5 by means of a pin 7 is a cylinder 8. Slidably mounted within the cylinder 8 is a piston 9 to which is attached a piston rod 10. The piston rod 10 passes through a guide 11 secured to the bottom of the cylinder 8, which holds the piston in alignment. The piston 9 is of an ordinary type and has a leather packing 91 which prevents air from passing around the piston. Placed inside of this packing 91 in order to take up space and thereby reduce the volume of fluid used, is a filler 92. The piston rod 10 extends downwardly and is secured to a piston 87 which operates within a small cylinder 12, attached to a cylinder head 13 pivotally connected by means of a pin 14 to the frame 1. The piston 87 has mounted thereon a pair of piston rings 93 which prevent flow of air around the end of the piston. Secured to the piston rod 10 near the cylinder 8 is a block 15, and adjustably secured to the small cylinder 12 by means of screw threads 16 is a second block 17. This block 17 is held in its proper position by means of a lock nut 18 that is also screw threaded to the cylinder 12. Extending between the two blocks 15 and 17 and pivotally connected thereto by pins 19 and 20 respectively, is a toggle arrangement 21. This toggle arrangement consists of two pairs of levers 22 and 23 pivotally interconnected by means of pins 24. The pins 19 and 20 pass through apertures 25 and 26 slightly larger than the pins and the ends of the levers 22 and 23 are rounded at 27 and 28. These rounded portions of the levers rest against blocks as shown at 29 and 30 which blocks are slightly rounded in order to provide a bearing surface for the rounded ends of the levers. The reason for this construction will be explained more fully hereinafter.

Mounted on a bracket 31 attached to the block 17, is a valve 32. This valve is operated by angular movement of a shaft 33, to which is attached a lever 34. Lever 34 is pivotally secured to the shaft 33 by a pin 35 in such manner that the lever can be rocked in a direction parallel to the axis of the shaft 33. This lever is held in position at right angles to the shaft 33 by means of a spring 36 and tends to be rotated in a right-handed direction as viewed in Fig. 2 by a tension spring 37. Attached to one of the levers 22 is an arm 38 which serves when the toggle is in the position shown in full lines in Fig. 2, corresponding to closed position of the press, to strike against the end of the lever 34 and maintain the valve 32 in an open position, as will be explained more fully hereinafter. At-

tached to the valve 32 are two pipes 39 and 40 which extend respectively to the cylinder 8 and an air compressor, or other source of fluid under pressure 41. Secured to each of the levers 22 is an arm 42 to which is attached an inclined member or cam face 43 and a thrust block 44. The block 44 is provided at its top side with a depression 45. Cooperating with the arms 42 in a manner to be later explained in detail is a pivotally mounted rod 46 which is attached to a bracket 47 secured to the cylinder 8 by means of a pin 48. The rod 46 is held in a neutral or center position by means of two tension springs 49 and 50 which are attached to the bracket 47 and to the rod 46. Passing through the lower end of the rod 46 and keyed thereto is a second rod 51 which is provided at each end with a flattened portion 52, which flattened portions, in certain positions of the rod, engage with the inclined members 43 and the blocks 44 of arms 42.

Secured to the lever arm 5 and to the frame 1 is a spring 53 which tends to move the lever arm 5 in such manner as to separate the presser head 6 from the buck 4. Secured to each side of the head of the cylinder 8 and the block 15 is a spring 54 which tends to draw the cylinder toward the block and thus effectively move the piston 9 upwardly within the cylinder. In order to permit the easy movement of the piston 9 in the downward direction a vent 55 is provided in the guide 11. This is necessary because the guide is made in such manner as entirely to close the end of the cylinder 8 so as to keep out dust or foreign matter. For the admission of fluid to the cylinder 12 a pair of tubes 56 and 57 are provided. Tube 56 leads from the air compressor 41 to a valve 58 mounted on the front side of the table 2 and tube 57 leads from this valve to the cylinder 12. For the operation of valve 58 to control admission of fluid to cylinder 12 is provided a pair of levers 59 and 60. Lever 59 is pivotally secured at 61 to arm 62 which is connected to the oscillating shaft 63 of the valve 58 (Fig. 6). Lever 60 is pivotally mounted at 64 and has secured thereto a projection 65. The valve 57 is controlled by rocking the arm 62, this rocking being accomplished by lifting the ends of both levers 59 and 60. The lengths of these levers and their pivot points are relatively so arranged that the lifting of one of the levers alone will not operate the valve, that is to say, if the lever 59 alone is lifted it will pivot around point 61 until the right-hand end of the lever strikes against the stop 66, without moving the arm 62 at all. In the same manner if lever 59 is left alone and lever 60 lifted this lever will pivot around 64 and strike against the stop 67 before the projection 65 strikes against point 68 of lever 59, hence no movement of the arm 62 will result. However, if both levers are lifted simultaneously the point 68 of lever 59 will strike against pro-

jection 65 of lever 60 so that the lever 59 will pivot around projection 65, thus causing the arm 62 to be rocked and the valve operated.

While valves 32 and 58 may be of any well known type, I prefer to utilize the special form of valve which for its operation requires but slight movement of its controlling member.

Referring more particularly to Figs. 3 and 4, the form of valve which I use comprises a housing 68 having screw-threaded in one side thereof a bearing member 70 in which is journalled a shaft 69. This shaft 69 has attached to its free end the lever 34 which is secured to the shaft in a pivotal manner by the pin 35 in a manner described more fully in the preceding discussion. Screw-threaded in the housing 68 are two plugs 71 and 72 which have threaded in their inner ends valve seats 73 and 74 respectively with which cooperate ball valves 75 and 76 respectively. For keeping ball 75 down on the seat 73 a plunger 77 and a spring 78 are provided. Likewise, for keeping the ball 76 on its seat 74 a plunger 79 and a spring 80 are provided. Secured to the end of shaft 69 is a finger member 81 which has a forked end portion 82 which engages ball 75, and a projecting end portion 83 which engages the ball 76. Fluid under pressure is supplied to the valve through an inlet pipe 84 and when the valve is open flows out of the valve through an outlet pipe 85. An exhaust pipe for the valve is provided at 86.

The operation of the valve is as follows:

When the member 81 is in the position shown in Fig. 3 both of balls 75 and 76 are on their seats and hence no fluid can flow into inlet pipe 84 or out of exhaust pipe 86. However, when the member 81 is rocked in a right-hand direction ball 75 is lifted off its seat 73 allowing fluid in the valve to escape through exhaust pipe 86. When member 81 is rocked in the opposite direction ball 75 is retained on its seat while the ball 76 is lifted from its seat, thus allowing fluid to flow into the valve through the inlet pipe 84 and out of the valve through the outlet pipe 85.

It will be understood that mushroom or flat valve members might be used in place of the balls 75 and 76, in which case, if desirable, the seats of the valve members might be provided with suitable gaskets of leather or the like.

The operation of the press is as follows:

When it is desired to close the press from its open position, as shown in Fig. 7, the operator lifts the ends of the two levers 59 and 60, more clearly shown in Fig. 6, thus opening the valve 58 to allow compressed air to pass from the air compressor 41 to the small cylinder 12. Air passes into the cylinder 12 and acts on the piston 87, causing the same and the connecting rod 10 to be thrust upward. On the upward movement of the rod 10 the block 15 strikes against the

lower end of guide 11, thus causing the cylinder 8 and left-hand end of lever arm 5 to be raised vertically and the head 6 to be lowered toward the buck 4. This action continues until the head is about to touch the buck. 75 When such position is reached the toggle arrangement 21 is in straightened position so that the levers 22 and 23 are very nearly in a straight line with each other. As the piston 87 continues to move upwardly the 75 lever arms 22 and 23 fully straighten out causing the arm 38 to strike against lever 34 of the valve 32 and rock the same in a left-handed direction. This rocking of the lever causes ball 76 to be lifted from its seat, thus 80 allowing air to pass into the valve from the air compressor 41 through the inlet 85 and to the cylinder 8 through pipe 39. Air entering the cylinder 8 acts on the piston 9. The piston 9 is now immovable due to the fact 85 that the toggle arrangement 21 has straightened out to the position shown in Figs. 1 and 2, hence the cylinder 8 is caused to move in an upward direction, thus rocking the lever arm 5 and thrusting the presser buck 6 down 90 on to the buck 4. As the area of the piston 9 is relatively large the pressure exerted on the head 6 is relatively very great. It will be noted that the lever arms 22 and 23 are provided at their interconnecting ends with 95 square bearing faces 88 and 89. These faces cause the levers when the toggle is straightened, to assume a position with their axis on the same straight line so that any pressure applied to the block 15 through the piston 100 rod 10 will not cause the levers to swing around the pivot point 24. If desired further assurance may be had that the levers 22 and 23 shall not open under pressure by making the toggle arrangements snap slightly 105 by center, that is to say, by making the faces 88 and 89 slightly at an angle so that the levers 22 and 23 will be tilted slightly to the left of the center line drawn between the two blocks 15 and 17. This positioning of 110 the levers will cause the toggle to tend to open in a left-handed direction, which opening would be prevented by the pin 24.

As the pressure applied to the head 6 is very great, say in the neighborhood of 2,000 115 pounds, it is necessary that the power mechanism be very strong. With this end in view bearing blocks 29 and 30 have been provided at the ends of the levers 22 and 23. Both the faces of the blocks and the ends of 120 the levers are rounded so that a bearing surface is provided. The blocks 29 and 30 are securely attached to the blocks 15 and 17, and through this arrangement any pressure applied to the rod 10 is transmitted through 125 the blocks 29 and 30 to the levers 22 and 23. In order to insure that the pins 19 and 20 will not receive any of the heavy pressure these pins are made slightly smaller than the holes 25 and 26 in the levers within which they fit. 130

This slight difference in the diameter of the pins and the holes permits the rounded ends of the levers to thrust against the blocks 29 and 30 and receive the full effect of the applied pressure.

During the closing movement of the press the arm 42 attached to lever 22 is swung around from the position shown in Fig. 7 to that shown in Figs. 1 and 2. In swinging 10 from one position to the other the inclined members or cam faces 43, attached to the arms 42, engage with the ends 52 of the rod 51, thus causing the rod to be swung in a left-handed direction against the tension of 15 spring 50. As the arm 42 continues to swing into position the ends 52 of the rod 51 slip outwardly and downwardly over the ends of the inclined members 43. Finally, after 20 the levers 22 and 23 have assumed the straight position shown in Figs. 1 and 2, but before the cylinder has had a chance to move upwardly under the pressure of the fluid admitted thereto by the action of the valve 32, the ends 52 of the rod 51 engage with the sides 25 of blocks 44. Then, as soon as the cylinder 8 moves upwardly under the fluid pressure applied thereto the rod 46 snaps back into 30 neutral position under the influence of spring 50, positioning end portions 52 over the de- pressions 45 in the blocks 44.

Opening of the press is accomplished by pulling a chain 90 attached to lever 34 of valve 32 and running over a pulley 91 secured to a bracket 92 mounted on the block 17 to the 35 front of the machine, as shown in Fig. 6. The pulling of the chain 90 causes lever 34 to be rocked longitudinally of the shaft 69, thus causing the end of the lever to disengage the arm 38 and snap into a normal position under 40 the action of tension spring 37. This movement of the lever 34 causes the ball 75 to be lifted off its seat while the ball 76 is held on its seat, both under the influence of the spring 45 and the pressure of the air applied to the inlet pipe. Air in the cylinder 8 now rushes out through the pipe 39 and exhaust 86, permitting the piston 9 to approach the cylinder 8 under the influence of tension springs 54. As the cylinder moves downwardly the rod 46 causes the ends 52 of rod 51 to strike 50 against the blocks 44 attached to arms 42, thus rotating the arms around pin 19 as a center and thereby opening the toggle mechanism and permitting the piston rod 10 to move downwardly under the influence of tension springs 53. As piston rod 10 moves downwardly and the piston 87 slides downwardly in the cylinder 12, the lever arm 5 rocks about its pivot point moving the presser head 6 away from the buck 4. The depressions 45 cooperating with the flattened portions of the rod 52 assure that the ends of the rod will not slip off from the ends of the blocks 44 as the arms 42 rotate around the 55 pin 19, and open the toggle arrangement 21.

The inclined member 43 strikes the top side of the end portions 52 of the rod 51, thus causing the rod 46 to be rotated in a right-handed direction against the action of the spring 49 sufficiently to permit the inclined portion 43 70 to clear the ends of the rod 51. After this clearance has been obtained the rod 46 snaps back into neutral position under the influence of spring 49 and is ready for another closing of the press.

The valve 58, which may be constructed in the same manner as the valve 32, is so arranged that when the lever arms 59 and 60 are in idle position the pipe 57 is open to the atmosphere through the valve. This permits 80 the piston 87 to slide into the cylinder 12 freely.

From the preceding description it is apparent that in closing the press it is necessary merely to raise the levers 59 and 60, which requires the use of both hands thus protecting the operator from injury due to accidental thrusting of the hands between the moving presser head and buck, hold the levers in raised position until the press has closed or 90 very nearly closed, then release the levers, the final heavy pressure being supplied to the press automatically, this heavy pressure continuing as long as the operator desires. Opening of the press, as stated above, is accomplished merely by pulling on the chain 90.

Adjustment may be made to accommodate the press to goods of different orders of thickness, by means of the screw threads 16 and lock nut 18, which secure the block 17 in position. In adjusting the press to thicker goods the lock nut 18 is loosened, the block 17 screwed toward the bottom of the cylinder 12, and the lock nut tightened. This adjustment would permit the toggle mechanism to 100 lock before any heavy pressure was applied to the goods in the press.

It will be seen that a press constructed in accordance with my invention is extremely easy to operate as no direct manual labor is 110 required for the opening or closing of the press. This construction renders it very easy for a person to operate the press during an entire working day with ease. A further advantage of this press is that it is necessary 115 for the operator merely to hold the control levers of the press in operating condition long enough initially to close the press, then to release the levers and go about their duties, while the heavy pressure is applied to the 120 press automatically. Because of this arrangement it is possible for an operator to work more than one press at the same time.

I have disclosed a particular embodiment of my invention merely for the purpose of 125 illustration and wish it understood that various modifications and adaptations of the device, such as would occur to one skilled in the art, may be made, and that I wish to be limited only by the scope of the following 130

claims as interpreted in view of the prior art.

What I claim is:

1. In a pressing machine, a valve control mechanism comprising a rotatable valve member, an arm attached to said member, a lever pivotally connected intermediate its ends to said arm, a second lever pivotally connected at one end to a fixed point and at an intermediate point engaging one end of the first mentioned lever, said levers serving, upon movement of their free ends, to rotate said valve member and thereby operate said valve.

2. In a two-hand control mechanism, an element, a lever mounted adjacent to said element and adapted to move it upon movement of said lever, a fulcrum for said lever and means for moving said fulcrum into and out of engagement with said lever, said lever and said means having hand grips for manual operation.

3. In a two-hand control mechanism, a movable element, a lever adapted to engage intermediate its ends with said element, a fulcrum for one end of said lever, and means for moving said fulcrum into and out of operative relation with respect to said lever.

4. In a pressing machine, a controlling mechanism comprising a movable member, a lever pivotally connected intermediate its ends to said member, a second lever pivotally connected at one end to a fixed point and at an intermediate point engaging one end of the first mentioned lever, said levers serving, upon movement of their free ends, to move said movable member and thereby actuate said controlling mechanism.

5. In a pressing machine, a controlling mechanism comprising a movable member, a lever pivotally connected at a bearing point to said member, a second lever pivotally connected at one point to a fixed member and at another point engaging with the lever first mentioned, at a point remote from said bearing point, said levers serving upon movement of their free ends, to move said movable member and thereby actuate said controlling mechanism.

In testimony whereof, I have signed my name to this specification, this 9th day of January 1928.

ERNEST D. ANDERSON.
